UNITED STATES PATENT OFFICE.

SCOTT McGEHEE THOMPSON, OF THE UNITED STATES NAVY.

GUN CONTROL.

1,342,475.

Specification of Letters Patent.

Patented June 8, 1920.

Application filed April 22, 1918. Serial No. 230,159.

To all whom it may concern:

Be it known that I, SCOTT M. THOMPSON, a citizen of the United States, an officer in the United States Navy, have invented 5 certain new and useful Improvements in Gun Controls, of which the following is a specification.

My invention relates to improvements in gun controls, and it consists in the constructions, combinations and arrangements 10 herein described and claimed.

An object of my invention is to provide a device for controlling a gun and especially one mounted on the deck of a vessel, 15 to keep the gun in a normally horizontal position, or in any other predetermined position, regardless of the roll of the vessel.

Another object of the invention is to provide a device for the purpose described, 20 consisting of an electrically operated mechanism arranged to be mounted upon a gun and adapted to control certain motor operated devices for elevating and depressing the gun to keep the gun trained on the 25 target regardless of the roll of the vessel.

Other objects and advantages will appear in the following specification, reference being had to the accompanying drawing in which:

30 Figure 1 is a side elevation of a gun showing one way of applying the invention.

Fig. 2 is a sectional view of the gun control showing the position of the parts 35 when the gun moves to an elevated position, and

Fig. 3 is a detail sectional view of a modification hereinafter to be described.

In carrying out my invention I provide 40 a batten 1 which is arranged to be mounted upon a gun 2 in any suitable manner and in actual practice will preferably be mounted adjacent to the usual telescope sights. In Fig. 1 the batten 1 is shown mounted on 45 the gun at the side simply to show the relationship of the gun control to the gun, and no attempt to show the sight referred to has been made.

Mounted upon the batten 1 is a U-tube 3 50 which is made of glass or some other substantial dielectric material. A bridge piece 4 forms the continuation of the tube at the top and closes the ends. Couplings 5 hold the bridge piece 4 in place but the joints

between the bridge piece and the U-tube 55 are not intended to be air-tight, nor is the space above the mercury 6 in the U-tube 3 intended to contain a vacuum. In the operation of the device it is necessary that the mercury column in each of the legs 60 of the tube be free to move up and down according to the rolling of the vessel 7 upon which the gun 2 is mounted.

Fixed in the left leg of the U-tube 3 and just below the coupling 5 is a contact 8 65 which is connected through a wire 9 to one terminal of a battery or other source of electrical energy 10. A movable contact 11 floats in the mercury 6 beneath the fixed contact 8 and normally engages the contact 8 when the gun 2 is in a true horizontal 70 position or when the batten 1 has been adjusted to bring the level of the mercury 6 into a true horizontal plane at such a time when the gun is trained on a target 75 at an angle either above or below the horizontal. A second contact 12 is fixed in the bottom of the tube 3 and is connected through a wire 13 to one end of the coil of an electro-magnet 14. The other end 80 of the electro-magnet is connected through a wire 15 to the other terminal of the battery 10 and when the float 11 is in engagement with the contact 8 a current flows from the battery 10 through the connections just 85 described, energizing the electro-magnet 14 and normally attracting a pivoted armature 16.

An expansion spring 17 is adapted to press the armature 16 into engagement with 90 a fixed contact 18 forming one terminal of a circuit 19 which embraces the motor M and generator G. The other terminal of the circuit is connected to the armature 16 as shown in Fig. 2, and when the electro- 95 magnet 14 is deenergized as in the instance when the ship rolls to one side or the other, the armature 16 is made to engage the contact 18 and close the motor circuit, whereupon the gun 2 is depressed or elevated to 100 counteract the roll of the ship, and again assume the position to which it was formerly trained.

One way of depressing the gun 2 as just described consists of fixing a gear segment 105 20 to the gun and providing a pinion 21 on the end of the motor shaft M for rotating the segment in a counter-clockwise

direction to depress the gun. Before proceeding with the description, it must be understood that there is a duplicate mechanism on the other side of the gun to that shown in Fig. 1. The other mechanism is not shown in the drawing but is so arranged that it will elevate the gun. In order to do this, the duplicate U-tube 3 on the other side will be arranged exactly the reverse of what is shown in Fig. 2, that is to say, the float 11 and contact 8 will be in the other leg of the U-tube so that when the vessel rolls toward the left instead of toward the right as indicated by the arrow *a* in Fig. 1, the circuit of the elevating motor on the other side will be completed in precisely the same manner as was just explained above. It is thought unnecessary, however, to go into detail, either as regards the description of the duplicate mechanism or the illustration thereof, since the operation of the automatic gun control can be fully understood when the manner of depressing the gun to counteract the roll of the vessel toward the right is fully explained.

In order to compensate for the expansion of the mercury 6 in the U-tube 3 and to offset the inaccurate operation of the device as a consequence, a compensator is attached to the bottom of the U-tube as shown in Fig. 2. The compensator consists of a cylinder 22 in communication with the U-tube, and has a piston 23 which is normally held in position by a light coil spring 24 between the bottom of the piston and the bottom of the cylinder. Auxiliary cylinders 25 at the sides have pistons 26 which rest on short columns of mercury 27. Suitably arranged levers 28 pivoted in the partition between the various cylinders, rest on top of the pistons 26 and in notches 29 of the piston 23 respectively. When the expansion of the mercury begins to take place, the columns 27 will force the pistons 26 upwardly and consequently force the piston 23 and the cylinder 22 downwardly against the tension of the light coil spring 24, when a corresponding quantity of the mercury 6 in the U-tube 3 will flow into the cylinder 22 on top of the piston 23 and thus compensate for the expansion of the mercury 6 in the tube 3. The level of the mercury in the tube 3 is thus kept in a substantially normal plane.

By way of adjustment of the batten 1 on the gun 2 a simple arrangement is shown in Fig. 1, which consists of a pivot bolt 30 and a thumb screw 31 threaded on the end of a stud in an arcuate slot 32. The need for a means of adjustment for the batten 1 will be understood by those practised in using naval guns. Instances often occur where the gun 2 will be elevated or trained on a distant target. At such a time the gun will not be in a true horizontal plane and conse-

quently the batten 1 must be adjusted to bring the level of the mercury 6 in the U-tube 3 to the horizontal plane or the normal position. Now when the vessel rolls the operation will be just the same as formerly and the motor devices controlled by the contacts in the U-tube will serve to keep the gun trained on the target.

A fluid other than mercury may be used to fill the U-tube 3. Such a fluid may be a non-conductor of electricity and when such a fluid is used the arrangement will be somewhat on the order as illustrated in Fig. 3. Here a pivoted bell crank or lever 33 is located inside of the U-tube 3 and is adapted to normally engage the contact 8 which in the present instance is almost flush with the wall of the U-tube. The float 11 has a fine wire 34 attached to the lower end, and the extremity of the wire is connected to the fixed contact 12. The wire 34 is not taut but has a small spiral or coil near the float 11 so that the wire may properly lengthen or shorten, or in any event, permit freedom of movement of the float 11.

The operation of the automatic gun control will be fully understood from the foregoing description, when taken in connection with the following additional explanation.

It is now assumed that the gun 2 is in a true horizontal position and has a duplicate controlling mechanism on the other side. This mechanism will however not be considered and the manner of depressing the gun to counteract the roll of the vessel 7 toward the right in Fig. 1, will be described.

Should the vessel roll toward the right as indicated by the full line arrow *a*, the batten 1 and gun 2 will tend to move to the position illustrated in Fig. 2 when the mercury column in the right leg of the U-tube 3 will ascend and the mercury in the left leg will consequently descend. The float 11 and contact 8 are normally in engagement as shown in Fig. 1, and when this is the case, the circuit from the battery 10 is completed through the electro-magnet 14 and the electro-magnet holds the armature 16 against the tension of the spring 17. Now when the mercury column in the left leg of the U-tube descends as just stated, the contact 8 and float 11 will break engagement and consequently break the circuit of the battery whereupon the armature 16 falls into engagement with the contact 18. Current from the generator G or other source of electrical energy then flows through the motor M which then operates to rotate the segment 20 in a counter-clockwise direction, causing the depression of the gun 2 in the direction of the dotted arrow in Fig. 1 to the normal horizontal position.

It is recognized that the motor M may not respond quickly enough to act in the manner just described and with this possible

defect in view, it is contemplated to employ some other device which will respond more quickly. The whole substance of the present invention is, however, the arrangement of 5 the automatic gun control and relates more particularly to the U-tube 3 with the movable contact therein. This is the basis of the invention and may be used in other connections equally as well as with a gun.

10 It is unnecessary to enlarge upon the advantages of the automatic gun control when used in the connection illustrated in the drawing, it being sufficient to say that the excessive movements and exertions gone 15 through by a gunner in keeping the gun trained on the target, are now practically entirely eliminated and instead of moving his shoulders and head three or four feet and changing his position from squatting to 20 standing while the vessel rolls rapidly, he needs only to move his head and eyes perhaps a few inches.

While the construction and arrangement of the device as illustrated in the accompanying drawing is that of a generally preferred form, obviously modification and changes may be made without departing from the spirit of the invention or the scope 25 of the claims.

30 I claim:—

1. The combination of an ordnance member to be trained, a prime mover for shifting the position of said ordnance member, a source of energy for said prime mover, 35 gravity actuated means for controlling the supply of energy from said source to said prime mover, and means for automatically compensating for physical changes in said gravity actuated means.

40 2. The combination of an ordnance member to be trained, a prime mover for shifting the position of said ordnance member, a source of energy for said prime mover, fluid gravity-actuated means for controlling 45 the supply of energy from said source to said prime mover, and means for automatically compensating for expansions and contractions of said fluid means.

3. The combination of an ordnance member to be trained, a prime mover for shifting the position of said ordnance member, a source of energy for said prime mover, a fluid gravity-controlled electricity conducting medium, contactor means operatively 55 associated with said medium for controlling the supply of electricity therethrough, and means for compensating for physical changes in said medium, to obviate variation of operation of said contactor means.

60 4. In a gun control, instrumentalities for controlling the operation of a prime mover by which the gun is actuated, comprising a conducting fluid influenced by gravity to maintain a normal plane, a dielectric con- 65 tainer for said fluid, operatively mounted to

move with the gun; contact making means operatively associated, including contacts carried by the container and a contact member supported by said fluid, and instrumentalities operatively associated with said container and fluid for compensating for physical changes in said fluid and thereby preventing changing of position of said normal plane. 70

5. In a gun control, the combination with 75 a motor circuit including a motor and a source of electrical energy, a batten adapted to be mounted on the gun, a U-tube mounted on the batten, contacts in one side leg and bottom of the U-tube respectively, 80 a relay including an electro-magnet having the terminals connected to said contacts, mercury in the U-tube extending into the legs, a floating contact in one side leg normally in engagement with the side contact 85 when the batten is in a horizontal position, an armature included in the relay attracted by the electro-magnet when the side and floating contacts are in engagement, to keep the motor circuit open, and a spring bearing 90 on the armature to close the motor circuit upon disengagement of the floating and side contacts when the batten moves out of the horizontal position.

6. In a gun control, the combination of 95 a motor circuit including a motor and source of electrical energy, a relay including an electro-magnet and armature adapted to close the motor circuit, a batten adapted to be mounted on a gun, a U-tube supported 100 on the batten, contacts in one side leg and the bottom of the U-tube connected to the terminals of the electro-magnet, mercury in the U-tube extending into the legs, a floating contact in one of the side legs, in normal engagement with the side contact when the batten is in the horizontal position, keeping the electro-magnet energized and the armature attracted to keep the motor circuit open, and means in connection with the U- 105 tube compensating for the expansion of the mercury therein, said means including a cylinder with an outwardly movable piston, adapted to receive a portion of the mercury from the U-tube, and auxiliary mercury 110 operated pistons having operating connection with said piston.

7. In a gun control, a batten adapted to be mounted on a gun, having an arcuate slot, a pivotal support and adjusting means in 1120 the arcuate slot, a U-tube mounted on the batten, a bridge piece forming a continuation of the open ends of the tube, couplings joining the bridge piece to the legs of the tube, fixed contacts in one side leg and the 1125 bottom of the tube, mercury in the U-tube extending into the side legs, a floating contact in the mercury in one side leg adapted to engage the side contact, compensating means including a downwardly extending 130

cylinder, auxiliary cylinders, a piston in the main cylinder, a coil spring beneath the piston, pistons in the auxiliary cylinders, expansible mercury columns beneath said 5 pistons, and lever connections between said pistons and the main piston to depress said piston in the main cylinder and permit mer-

cury from the U-tube to flow into said main cylinder, upon elevation of the auxiliary pistons by the expansion of the mercury 10 columns.

SCOTT McGEHEE THOMPSON.
